UNITED STATES PATENT OFFICE.

CHARLES A. RANDALL, OF NEW YORK, N. Y.

TELEPHONIC RECEIVER.

SPECIFICATION forming part of Letters Patent No. 241,065, dated May 3, 1881.

Application filed February 4, 1881. (No model.)

To all whom it may concern:

Be it known that I, CHARLES A. RANDALL, a citizen of the United States, residing at New York city, New York, have invented new and 5 useful Improvements in Telephonic Receivers, of which the following is a specification.

This invention relates to an articulating telephonic receiver for use in connection with a battery-transmitter—that is, a transmitter of that 10 class in which the vibrations of a diaphragm or other vibrator cause a variation in a battery-current, and also of that class in which the vibrations of a diaphragm or other vibrator cause an actual make and break of the battery-current which traverses the line and controls the 15 action of an electro-magnet upon the diaphragm or other vibrator of the receiver.

The object of my invention is to obviate the production of those inarticulate drumming 20 sounds which are often mingled with the articulate communication delivered by the receiver, and which are usually caused by breaks of the circuit, resulting from speaking too loud in front of the transmitter, and thus causing 25 vibrations of excessive amplitude in its diaphragm or other vibrator, such excess of movement separating the contact-points of the transmitter too long or irregularly, and thus unduly breaking the circuit and causing abrupt dis- 30 charge or demagnetization, and recharge or magnetization of the electro-magnet of the receiver, these abrupt discharges and recharges resulting in sudden and violent vibrations of 35 the receiver-diaphragm or other vibrator and the production thereby of the objectionable sounds before referred to.

The invention also has in view the construction of an electro-magnet in such a manner that its core will continue to be magnetized to a degree after the cessation of flow of the prime electric current which enlivens it, and thus abrupt discharge be prevented, and the action of the core extended during a time sufficient for the re-establishment of the continuity of the circuit when it has been broken by the excessive vibration of a transmitter-diaphragm or other vibrator, so that a continuous action of the electro-magnet upon its armature is maintained, and movements caused by it in a receiver-di- 45 phragm or vibrator will have an undulatory 50 character, causing air-vibrations producing ar-

ticulate sounds corresponding to those at the transmitter, instead of abrupt and violent vibrations, which would result from the sudden discharge and recharge of the receiver-magnet. 55

Another object of my improvement is to produce an extensive amplitude of vibration in the diaphragm or other vibrator of a telephonic receiver, and thus promote distinctness and 60 volume in the sounds emanating therefrom.

In the accompanying drawings, Figure 1 is a section through a telephonic receiver constructed according to my invention, and Fig. 2 is a section of a receiver in which the magnet acts directly upon the diaphragm or vi- 65 brator.

The letter A indicates a box or case, having in one wall an aperture closed by a diaphragm or sounding-plate, B, which is surrounded by an ear-piece, C, the inner edge of which serves 70 to hold the surrounding plate in place.

The letter D designates an electro-magnet constructed according to my invention, and composed of a soft-iron core, E, surrounded directly by a primary helix, F, of comparatively 75 coarse wire, the terminals of which are connected with the screw-posts g and g', respectively, a secondary helix, H, surrounding said helix and formed of finer wire, and an auxiliary coil, I, surrounding the portion of the core 80 projecting beyond the primary coil and having its terminals connected, respectively, with those of the secondary helix H, as shown at k k'. An armature, L, secured to a lever, M, pivoted at m, is arranged to face the end of the core E, 85 and the upper end of the lever M is connected by a light rod, N, with the center of the sounding-plate or may simply impinge thereon. The auxiliary coil I is wound in proper direction to induce in the core a polarity similar to that 90 caused by the primary helix. The line-wire is to be connected to one of the screw-posts g or g' and the other post connected with the ground.

When electrical impulses are caused by a 95 transmitter to traverse the line and primary helix F the magnet-core E, in response to these impulses, acts upon the armature L, causing the lever M to vibrate and communicate vibrations having an amplitude much greater 100 than could be produced by the direct action of the magnet upon the plate, as the extent of

movement of the free end of the lever is obviously much greater than the distance through which the magnet could effectively exercise its attractive power upon a confined diaphragm. 5 By this arrangement I secure the production by the sounding-plate of sounds of great volume and distinctness, and relieve the listener of the strain occasioned by the close attention heretofore necessary to catch the words of telephonic receivers. When the circuit is broken at the transmitter by the cause heretofore referred to, or any other, the core E of the receiver is not instantly demagnetized and suddenly remagnetized when the circuit is re-established, for the instant the current ceases to flow in the primary helix F, an induced current flows over the secondary helix H, and thence over the auxiliary coil I, thus inducing in the core a continuance of its magnetization, which 5 maintains unbroken or only gradually loses its control of the armature L, so that sudden and violent vibrations of the sounding-plate are prevented, as already explained.

In Fig. 2 the magnet, as described with reference to Fig. 1, is shown as arranged to act directly upon the diaphragm or sounding-plate B', and the armature, lever, and connecting-rod omitted.

The operation of the magnet, as far as is concerned the continuance of action, is the same in 30 the modification as before explained, a metallic diaphragm or vibrator being used.

What I claim is—

1. In a telephonic receiver, the combination, 35 with a sounding-plate or vibrator, of the electro-magnet D, composed of the core, primary and secondary helices, and the auxiliary coil connected with said secondary helix, substantially as described.

2. In a telephonic receiver, the combination, 40 with the sounding-plate or vibrator, of the electro-magnet composed of the core, the primary and secondary helices, and the auxiliary coil connected with said secondary helix, and the armature L, the lever carrying said armature 45 and the rod connecting said lever with the diaphragm or vibrator, substantially as described.

In testimony whereof I have hereunto set my hand in the presence of two subscribing witnesses.

CHARLES ADAMS RANDALL.
